UNITED STATES PATENT OFFICE.

JOHN AUGUST SWANSON, OF MINNEAPOLIS, MINNESOTA.

BOTTLE-HOLDER.

1,222,486.

Specification of Letters Patent. Patented Apr. 10, 1917.

Application filed May 3, 1915. Serial No. 25,493.

To all whom it may concern:

Be it known that I, JOHN AUGUST SWANSON, a citizen of the United States, residing at Minneapolis, in the county of Hennepin and State of Minnesota, have invented certain new and useful Improvements in Bottle-Holders; and I do hereby declare the following to be a full, clear, and exact description of the invention, such as will enable others skilled in the art to which it appertains to make and use the same.

My invention relates to improvements in folding bottle holders, especially adapted for use in holding milk bottles in folding grocery delivery boxes; and, to this end, it consists of the novel devices and combination of devices, hereinafter described and defined in the claim.

In the accompanying drawings, which illustrate the invention, like characters indicate like parts throughout the several views.

Referring to the drawings:—

Figure 1 is a perspective view of a folding grocery delivery box, having secured thereto two of the improved bottle holders, one of which is open and supporting a milk bottle within the box, and the other of which is folded, some parts of the box being broken away;

Fig. 2 is a perspective view of the box and bottle holders folded;

Fig. 3 is a side elevation of one of the improved bottle holders folded, on an enlarged scale;

Fig. 4 is a vertical section taken on the line $x^4 x^5$ of Fig. 3; and

Fig. 5 is a vertical section taken on the line $x^4 x^5$ showing the bottle holder open.

The numeral 1 indicates a folding grocery delivery box, and the numeral 2 indicates a milk bottle.

The improved bottle holder comprises a yoke 3 and a saddle bracket 4. As shown, the yoke 3 is made from a single piece of wire, bent upon itself to form the yoke and a pair of rearwardly projecting prongs 5. The free ends of these prongs 5 are bent inwardly, in axial alinement, to form a pair of trunnions 6, the inner ends of which are bent rearward in parallel arrangement to form a pair of lugs 7.

The yoke 3 is of annular form and of substantially the same diameter as that of the neck of the bottle 2. The yoke 3 extends more than one-half of the distance around the neck of the bottle 2, thereby requiring

the prongs of the yoke to be sprung apart in applying or removing the bottle therefrom.

The yoke 3 is attached to the saddle 60 bracket 4, with freedom for vertical folding movement to and from an operative position, by mounting its trunnions 6 in a pair of axially spaced hinge lugs 8, formed at the free end of a pair of spring arms 9. These 65 spring arms 9 are formed by cutting parallel slits in the inner plate of the saddle bracket 4, which extends from its lower edge upward. The hinge lugs 8 are formed by rolling the free ends of the arms 9. That 70 portion of the saddle bracket 4, between the arms 9, is bent laterally inward, just above the hinge lugs 8, to form a stop shoulder 10, and is then bent vertically downward to form a stop plate 11. This stop plate 11 75 bears directly against the adjacent face of the box 1, as a base of resistance.

When the yoke 3 is turned into an operative position, as shown in Fig. 5, its lugs 7 engage the stop shoulder 10, and thereby 80 hold said weight in a horizontal position. In turning the yoke 3 from a folded to an open position, its lugs 7 engage the stop plate 11, which acts as a base of resistance therefor, and yieldingly forces the arms 9 85 outward. The inward pressure of the arms 9 causes the ends of the lugs 7 to frictionally engage the stop plate 11 and thereby yieldingly hold the yoke 3 in an operative position. In the folded position of the yoke 3, 90 the spring arms 9 yieldingly hold the yoke 3 against the saddle bracket 4 with its lugs 7 extending substantially parallel to the stop plate 11, and engage the same to yieldingly hold the yoke 3 folded. 95

As shown, the saddle bracket 4 embraces the upper edge of one of the sides of the box 1 and is permanently secured thereto by a nut-equipped bolt 12 passed through alined perforations in the side plates of the saddle bracket and the box. By thus securing the saddle bracket 4 to the box 1, the bottle holder is always in position in the box, and when it is desired to fold the box, the yoke 3 is first folded, as shown in Fig. 4. When 100 the bottle holder is not in use, the yoke 3 is kept in a folded position so as to not interfere with the contents of the box. One or more of these improved bottle holders may be applied to a box. 105

The above described invention, while extremely simple and of small cost to manu-

facture, has, in actual usage, proven highly efficient for the purpose had in view. As previously stated, the yoke is formed from a single piece of wire, bent to proper form, 5 and the saddle bracket 4, arms 9, stop shoulder 10, and stop plate 11 are all formed from a single sheet of metal, cut and pressed to proper form.

What I claim is:

- 10 A bottle holder comprising a saddle bracket, and a yoke, said saddle bracket having a stop shoulder, a stop plate, and a pair of spring arms, having formed thereon hinge lugs, said yoke being made from a 15 single piece of wire, bent at its ends to form trunnions, and bent upon itself, at its inter-

mediate portion, to form a spring yoke, adapted to be sprung into engagement with the neck of a bottle, the trunnions of said yoke being mounted in said hinge lugs and being bent to form lugs, engageable with said stop shoulder to support the yoke in an operative position and engageable with said stop plate to yieldingly hold the yoke in its two extreme positions.

In testimony whereof I affix my signature in presence of two witnesses.

JOHN AUGUST SWANSON.
